UNITED STATES PATENT OFFICE

2,525,797

YARN STEAMER

Rae Harris, Chicago, Ill.

Application July 23, 1946, Serial No. 685,653

1 Claim. (Cl. 68—5)

1

The invention relates to a yarn racking device, and more especially to a yarn reconditioner.

The primary object of the invention is the provision of a device of this character, wherein used yarn can be reeled thereon in a manner that it can be conveniently reconditioned for removing kinks and wrinkles from the same, so that it may be reused and having the appearance as new yarn in the knitting thereof.

Another object of the invention is the provision of a device of this character, wherein the same is in the form of a rack having a reel appearance, with a handle extension for carrying a conical wooden plug, which is insertable in the pouring spout of a water kettle or the like during unreeeling of the yarn, so that when the yarn is upon the rack it can be subjected to steam or hot vapors from the contents of the kettle, whereby the yarn will be reconditioned, that it may be used again, with removal of all kinks or wrinkles therein, and such reconditioned yarn can be readily and easily unwound from the reel with dispatch while attached to the kettle.

A further object of the invention is the provision of a rack of this character, which is simple in construction, thoroughly reliable and efficient in operation, strong, durable, readily and easily handled for reeling and unreeeling of yarn on and from the same, assuring quick reconditioning of the latter, and inexpensive to manufacture.

With these and other objects in view the invention consists in the features of construction, combination and arrangement of parts as will be hereinafter more fully described, illustrated in the accompanying drawing, which discloses the preferred embodiment of the invention, and pointed out in the claim hereunto appended.

In the accompanying drawing:

Figure 1 is a perspective view of the device constructed in accordance with the invention.

Figure 2 is a fragmentary longitudinal sectional view through the handle extension of the device.

Figure 3 is a fragmentary inside face view of one side edging of the device.

Figure 4 is a side elevation of the structure shown in Figure 3.

Figure 5 is a side elevation of a kettle showing the device attached thereto for reconditioning purposes of the yarn upon the device.

Figure 6 is a sectional view taken approximately on the line 6—6 of Figure 1 looking in the direction of the arrows.

Similar reference characters indicate corresponding parts throughout the several views in the drawing.

2

Referring to the drawing in detail, yarn rack constituting the present invention, comprises a centrally open racking frame A, preferably made from a single length of wire of the selected gauge to give the required rigidity thereto, and this frame involves opposed spaced parallel straight side runs 10, opposite outer and inner spaced cross connecting end runs 11 and 12, respectively, which join with the side runs 10 by coiled corner portions 13 providing outwardly protruding abutments at opposite ends of these side runs 10 which are inset within the central opening of such frame A, as best seen in Figures 1 and 5 of the drawing.

10 The outer end run 11 is outwardly bowed, while the inner end run 12 is outwardly tapered in shape, and are continuations of the end portions of the wire forming the frame, which end portions are twisted together to effect an extension 15 handle 14, the latter being straight throughout the same.

15 On the handle is loosely fitted a conical plug 15, which is of a size to fit within the pouring spout 16 of water steaming kettle 17 of any 20 standard size and construction for domestic service, this fitting of the plug 15 being best shown in Figure 5 of the drawing, so that the rack will be supported by the kettle, to enable the reconditioning of yarn 18 when wound onto the 25 said frame A, by the steam emitted from such kettle, to remove kinks and wrinkles from the 30 said yarn after preuse thereof.

35 The used yarn 18 is unraveled from a knitted article, and wound on the frame A, by training over reeling plates or blades 19, which are longitudinally channeled at 20 for the seating of the side runs 10 therein, and the abutment of the 40 coiled corners 13 therewith for the holding of such plates or blades frictionally engaged on the frame, the corner portions 13 being for the 45 purpose of preventing the windings of the yarn 18 from slipping off of the frame while reeling or unreeeling of this yarn on and from the said frame A.

50 When the used yarn 18 has been completely wound on the frame A to the capacity thereof, the plug 15 is loosely inserted in the spout 16 of the kettle 17 which is placed on a heater for the steaming of the content thereof, which on 55 being emitted from the spout or open top of the kettle will pass through the clearances between plug 15 and the spout and between the plug 15 and the handle 14 (Fig. 2) to recondition the yarn on the rack to remove kinks and wrinkles therein. Also, the frame A may be manually

grasped by the extension 14 and held near the steaming spout for the same purpose. Thereafter, the kettle with the rack and yarn is removed from the heater to a place of safety, whereupon the yarn is unreeled from the frame A which rotates in the plug 15 for this purpose, while the said plug is engaged in the spout of the kettle for the reuse of the conditioned yarn as may be desired, the reconditioned yarn being now like new yarn.

What is claimed is:

A device for supporting yarn adjacent a source of steam comprising a racking frame formed from a single and continuous length of wire, said wire having a pair of spaced substantially parallel linear portions, a first and a second abutment portion on each end, respectively, of each of said linear portions, said abutments of each linear portion being convergent therefrom, an outer cross connecting portion, a substantially U-shaped portion at each end of said outer cross connecting portion connecting the same with said first abutment portions of said linear portions, respectively, inner connecting portions converging together and twisted together to form a laterally extending pivot handle, substantially U-shaped portions connecting said second abut-

ment portions to said inner connecting portions, respectively, plates on said linear portions frictionally held thereon by inherent resiliency of said abutment portions, said plates being adapted to receive the yarn and said abutments preventing slippage of yarn off said frame, and a plug adapted to be loosely inserted into a kettle spout and having an opening therethrough for loosely receiving said pivot handle whereby steam may be directed toward the yarn on the frame and whereby said pivot handle rotatably supports said frame on said plug during unwinding of the yarn.
